UNITED STATES PATENT OFFICE.

FREDERICK H. HINSDALE, OF ROANOKE, VIRGINIA.

LIQUID-APPLYING STOPPER FOR BOTTLES.

1,021,522.

Specification of Letters Patent. Patented Mar. 26, 1912.

Application filed April 6, 1911. Serial No. 619,293.

To all whom it may concern:

Be it known that I, FREDERICK H. HINSDALE, a citizen of the United States, residing at Roanoke, in the county of Roanoke 5 and State of Virginia, have invented certain new and useful Improvements in Liquid-Applying Stoppers for Bottles; and I do declare the following to be a full, clear, and exact description of the invention, such 10 as will enable others skilled in the art to which it appertains to make and use the same.

This invention relates to improvements in liquid applying stoppers for bottles.

15 The object of the invention is to provide a stopper of this character having an improved means for fastening the same to the mouth of the bottle and means for fastening a liquid applying sponge thereto, whereby 20 the liquid from the bottle may be freely discharged onto the sponge and the latter thus saturated with the liquid.

In devices of this kind now in general use, 25 it is almost invariably the case that the sponge rests closely upon the top of the cork and the latter is held in the mouth of the bottle only by its usual expansion. The former I find objectionable because when 30 this device is used for applying liquid blacking to shoes, for instance, pressure on the sponge soon causes the blacking to ooze out over the cork, whence it runs down the bottle and eventually soils the hand of the operator. The latter I find objectionable also, 35 because in the act of wiping the sponge across the shoe or other object treated, the cork is often loosened within the mouth of the bottle if held therein only by its usual friction, with the result that it comes out of 40 place and the liquid is spilled.

With this and other objects in view, the invention consists of certain novel features of construction, combination and arrangement of parts as will be more fully described 45 and particularly pointed out in the appended claim.

In the accompanying drawings: Figure 1 is a central vertical section through the upper end of a bottle showing the invention applied thereto; Fig. 2 is a detail perspective view of the combined cap and sponge holder of the device showing the position of the parts before being applied; Fig. 3 is a similar view of the upper end or mouth of the

bottle showing the manner in which the 55 same is constructed to receive the device.

My improved liquid applying stopper comprises a combined sponge holder 1, an attaching device 2 and a discharge tube 3, said parts being preferably formed integral 60 or constructed from one piece of metal. The sponge holder 1 comprises a hemispherical or cup shaped body portion having on its upper edge a plurality of prongs or teeth 4 which are adapted to be turned inwardly 65 and forced into engagement with the sponge 5 or other material provided for applying the liquid. The sponge holding cup 1 is connected by a short neck 6 to the attaching device 2 comprising a circular plate or disk 70 which preferably decreases in thickness from the central portion toward its outer edge and has formed on its outer edge an annular downwardly extending attaching flange 7 which when the device is applied to 75 the bottle is adapted to be turned inwardly and clenched into engagement with an annular rib or bead 8 formed on the upper end or mouth of the bottle.

In the center of the inner side of the disk 80 2 is formed the liquid discharging tube 3 the opening in which is continued up through the neck 6 and communicates with the sponge holding cup 1. In the center of the inner portion of the sponge is formed a 85 cavity or recess 9 into which the liquid from the discharge tube passes and which provides an increased area for absorbing or taking up the liquid discharged from the tube thus more quickly saturating the sponge. On 90 the tube 3 is arranged a cork or other form of stopper 10 which is adapted to closely fit and to be forced into the mouth of the bottle thus preventing any discharge of the fluid therefrom except through the tube 3. 95 The cork or stopper 10 is firmly secured in place on the tube 3 by an annular flange 11 formed on the inner end of the tube and engaging the inner end of the stopper as shown. 100

In order to prevent the sponge from drying out when not in use I provide an air tight cap or casing 12 which is preferably of cylindrical form and is provided on its inner end with screw threads 13 adapted to 105 be screwed into engagement with threads 14 formed on the outer side of the head of the bottle as shown. By means of the cap

12 the sponge will not only be prevented from becoming dry when not in use, but the contents of the bottle will also be prevented from evaporating, said cap forming an air
5 tight closure for the bottle. When it is desired to use the bottle the cap is removed and the bottle inverted to permit the contents thereof to pass through the tube 3 and onto the sponge or other applying material
10 thus saturating the latter whereupon the liquid may be applied to the surface to be coated by the sponge, using the bottle as a handle for operating the sponge.

15 While my invention is primarily intended as a means for containing and applying blacking to shoes, it is obvious that the same may be employed for applying any liquid preparation.

20 From the foregoing description taken in connection with the accompanying drawings, the construction and operation of the invention will be readily understood without requiring a more extended explanation.

25 Various changes in the form, proportion and the minor details of construction may be resorted to without departing from the

principle or sacrificing any of the advantages of the invention as defined in the appended claim.

Having thus described my invention, what 30 I claim is:

In a liquid applying stopper for bottles comprising a sponge-holding cup, a plate formed on said cup provided with an attaching flange whereby it may be attached 35 to the neck of a bottle, a discharge tube formed on and projecting from said plate, the bore of said tube being continued through the plate and bottom of the cup, a cork arranged on said tube, a flange on 40 the lower end of the tube to prevent the cork from becoming detached, a sponge arranged in the cup, and attaching teeth formed on the outer edge of the cup and adapted to be forced into said sponge. 45

In testimony whereof I have hereunto set my hand in presence of two subscribing witnesses.

FREDERICK H. HINSDALE.
